UNITED STATES PATENT OFFICE.

VICTOR REDLICH, OF VIENNA, AUSTRIA.

CENTRIFUGAL MACHINE.

Application filed May 4, 1926, Serial No. 106,735, and in Austria May 19, 1925.

Centrifugal machines of the type in which the liquid and the solid material are automatically and continuously delivered are known. The solid material is delivered 5 through openings in the sides of a non-perforated drum by means of a wheel having compartments which rotates in an annular channel of the said drum at a different velocity to the latter, the liquid being caused to leave the drum by being guided radially inwards and downwards and thereupon ejected.

The present invention has for its object to provide a centrifugal machine, in which 15 the liquid and solid material are delivered automatically and continuously one after the other at different points of the wall of the same drum, which for this purpose surrounds the drum provided with compartments, hereinafter referred to as the cell drum, in the form of a perforated drum, the liquid being thrown out through the meshes of the perforated drum against a non-perforated receiving wall which guides 20 it outward and the solid material through openings in the perforated drum and the said guiding wall.

When using the centrifugal machine in the manufacture of sugar where the fine 30 liquor or other liquid has to be fed in and the various liquids have to be separated, an important feature is that the cell drum (cleansing drum) shall be made in the form of a grid of a certain form, the construction 35 of the fixed outer wall also being an important feature.

In the accompanying drawing Figs. 1 and 2 show a constructional example of a centrifugal machine for use in the manufacture 40 of sugar, Fig. 1 being a vertical axial section on line C—D of Fig. 2 and Fig. 2 a transverse section on line A—B of Fig. 1. Figs. 3 to 5 show details.

Fig. 6 is a longitudinal section on line 45 6—6 of Fig. 7, partly shown in elevation.

Fig. 7 is a cross section along lines 7—7 of Fig. 6; and

Fig. 8 is a view in end elevation thereof.

In the example of the invention shown 50 in Figs. 1 and 2 of the drawing, 1 is a perforated drum, 2 a non-perforated wall surrounding the drum and connected to it for catching the liquid and guiding it downwards, 3 the cell drum (the expulsion drum) and 4 the stationary surrounding wall.

For automatically and continuously delivering the solid material after it has been freed by centrifugal action from the liquid the drum 1 and the surrounding wall 2 are provided, as shown in the drawing, with two oppositely located vertical or inclined slots 5, which extend almost over the whole height of the same, the cell drum 3 rotating in the same direction as the perforated drum 1 but at a different speed, which difference may in most cases be very small. For this purpose a transmission gear of a known kind, which is not shown in the drawing, is provided for transmitting the motion from the shaft 6 of the cell drum 3 to 60 the hollow shaft 7 of the perforated drum 1 or vice versa, so that the cell drum will rotate at a slightly lower or slightly higher speed than the perforated drum. The hollow shaft 7 is driven by means of beveled 65 gear 30 from the shaft 31. Fixed on the hollow shaft 7 is a transverse arm which has on one end a worm 33 and at the other end a balancing weight 34 for the worm. The worm drives a worm gear fixed on the 70 shaft 6 and carries on its axle 36 a fixed star wheel 37 which in the common rotation of the two shafts 6 and 7 engages with a tooth 75 a fixed or stationary inclined surface 38, where it is turned around its axis by such 80 an angle that in the next rotation the next tooth becomes engaged, and so forth. The consequence is that in each rotation of both shafts the shaft 6 is rotated relative to the shaft 7 by a certain angle, thereby the advanced movement or retarded movement of 85 the cell drum 1 relative to the screen drum 2 is effected. Furthermore, as the cell drum 3 is designed for carrying the solid material in the peripheral direction, being for 90 instance made in the form of a grid with grid openings lying next to one another or one above the other exactly or approximately 95 radially, the solid material, from which the liquid is continuously removed by centrifugal action, is moved, since the perforated drum rotates at a given speed, continuously and slowly to a slot 5, which each point on the cell drum reaches after a certain period of time, so that the solid material 100 is continuously delivered by centrifugal force to the stationary surrounding wall 4, from which it is mechanically removed at 12 around the entire periphery.

If the solid material is to be moulded, the 110

unshaded portions of the grid, that is the cells, are adapted to the size and shape of the product to be made, for instance, when the centrifugal machine is used in the manufacture of sugar, to the size of the cubes of sugar to be made.

The liquid which has been separated from the material passes through the perforated drum 1 against the non-perforated wall 2 from where it is removed downwardly through the inclined arrangement of the said non-perforated wall or under the action of gravity and can run off along the inclined bottom of the pan 13 at 14. The annular space between the drum 1 and the surrounding wall 2 may be divided up by substantially vertical walls 15 into segments, from which the liquid runs down in separate streams to the fixed pan 13. By this subdivision a relative rotation of the liquid with respect to the drum is prevented.

The material to be centrifuged is fed continuously by means of an arrangement which rotates at the velocity of the perforated drum 1 to that portion (segment) of the cell drum 3, from which previously the solid material was removed. In the example shown in the drawing this arrangement consists of a central feed pipe 16 which is connected in a suitable manner, for instance by a spider 17, to the perforated drum 1 and therefore rotates with the same. The pipe 16 has longitudinal slots 18 having about the same height as the drum, from which longitudinal slots extend substantially radial, narrow channels 19 of uniform width and of the same height as the drum, which may extend as far as the cell drum 3. A fixed feed pipe 27 opens into the pipe 16.

40 This arrangement acts in the following manner:

Let it be assumed that the drums 1 and 2 and consequently the feeding means 16, 19 rotate at a certain speed in the direction shown by the arrows in Fig. 2 and that the cell drum 3 which rotates in the same direction, has a slightly greater speed of rotation. The solid material will then be ejected continuously at the slots 5 to the width of the segments corresponding to the same out of the cells of the drum 3, the segments which have thus been emptied creeping, owing to the slightly higher speed of rotation of the drum 3, in the direction of the arrows with respect to the channels 19, through which the empty segments are filled with material to be treated under the action of centrifugal force. The end of the channels 19 may act as scrapers against the drum 3 or separate scrapers 19' may be provided, so as to provide for the material to be treated being always fed forward in a uniformly thick layer. The layers fed forward in this manner as well as the remainder of the material in the drum 3 are freed from the liq-

uid through the velocity at which the drum rotates and are gradually fed to a second slot 5, through which they are removed.

In centrifugal machines it is frequently required to feed in continuously one or more liquids, for instance in the manufacture of sugar the fine liquor or the like. The liquids are fed in by means of one or more devices which are similar to the feeding device for the material to be centrifuged, rotating at the same speed as the perforated drum, but displaced with respect to the said device in the direction of rotation. In the example shown in the drawing a pipe 20 surrounding the pipe 16 is provided, which is connected to the pipe 16 and consequently to the drums 1 and 2, with which it rotates. The pipe 20 is provided with a stationary feed pipe 28 and with longitudinal slots 21 of approximately the same height of the drums 1 and 2. Communicating with the said longitudinal slots are substantially radial, narrow channels 22 of the same height, which lead to the cell drum 3, but are displaced in the direction of rotation with respect to the channels 19, so that first the material to be centrifuged by itself and thereupon the fine liquor is fed to the emptied drum segment in a layer of as uniform a thickness as possible. In accordance with this displacement both the material to be centrifuged by itself and the said material after being supplied with the fine liquor has time to be thrown out by itself by centrifugal force, which makes it possible to catch two or more runnings separately in the surrounding wall 2 and to lead them away which is effected by the walls 15 already described, which divide the intermediate space between the drums 1 and 2 into segments. It is then only necessary to provide means for catching the liquids in separate, stationary containers. As is shown by way of example in Fig. 3 in vertical section on the line E—F of Fig. 4 and in Fig. 4 in horizontal section on line G—H of Fig. 3, the segment of the surrounding wall 2 which serves the purpose of leading away one of the liquids has an outer wall 2'', which is at a greater distance from the centre than the wall 2' of the segment which serves to lead away a second (or other) liquid, so that the liquids flowing down along the walls 2' and 2'' are caught in separate stationary containers 13 and 13' respectively and are lead away separately, which makes it possible to deal separately and therefore economically with two (or more) liquids.

When the cells of the cell drum 3 have the form and size of sugar cubes, the centrifugal machine may be used for the production and delivery of the finished sugar cubes, which will then only require drying. Care must then be taken that the cells shall be completely filled as accurately as possible, which may be effected by provision being made

- for the cell drum 3 to have a suitable speed relative to the feed channel 19, by the channel 19 having a suitable width with respect to the dimensions of the cell and by means 5 of the scrapers 19'. In order that the cubes of sugar shall not be broken by hitting against the stationary surrounding wall 4, owing to the centrifugal force with which they are thrown against it, they are retarded 10 when being thrown out by suitable guiding walls in a suitable manner. As shown in Fig. 5 in vertical section through the slot 5, stationary guiding walls 23 are provided, which extend completely round the machine 15 and form channels 24 which are curved or inclined with respect to the horizontal direction of delivery. As will be seen from this figure a delivery channel of this kind may be provided for each horizontal row of cubes 20 coming from the cell drum 3. The effect of these channels is to prevent the cubes from striking against vertical walls and to cause them to be deflected as gradually as possible from the direction in which they are 25 thrown out, whereby the velocity of the cubes is gradually retarded. The cubes can leave the machine in an inclined outlet 25, which is common to all the channels. Horizontal guiding walls may be provided 30 in the slots 5 of the drums 1 and 2 at the level of the horizontal walls of the cells and at the beginning end of the walls 23, for the purpose of guiding the cubes of sugar when thrown out.
- 35 The guiding walls 23 may also follow the direction in which the cubes are thrown out, that is they may be horizontal, as is shown in dot and dash lines at 23'. In this case the friction of the cubes against the walls 40 has the desired retarding effect. The cubes will then drop down against the wall 4', after which they can be removed.
- What I claim is:
- 45 1. A centrifugal machine including a cell drum, a feeding device for the material to be centrifuged, a perforated drum surrounding said cell drum and covering the cells at the circumference, a non-perforated wall surrounding the perforated drum and 50 connected to it so as to leave an annular space therebetween, the perforated drum and the wall having openings for delivering the solid material, means for rotating the two drums at a different velocity, the liquid 55 passing through the meshes of the perfo-
- rated drum against the non-perforated wall which catches it and guides it outward and the solid material passing through said openings.
2. A centrifugal machine as claimed in 60 claim 1, wherein the feeding device for the material to be centrifuged consists of a plurality of radial channels having means for closing tight at the inside of the cell drum.
3. A centrifugal machine as claimed in 65 claim 1, wherein a feeding device is provided for liquid and is displaceable in the direction of rotation of the cell drum with respect to the feeding device for the material to be centrifuged.
4. A centrifugal machine as claimed in 70 claim 1, wherein additional walls are arranged in the annular space between the perforated drum and the non-perforated wall to subdivide the same into segments.
5. A centrifugal machine as claimed in 75 claim 1, wherein additional walls are provided in the annular space between the perforated drum and the non-perforated wall for subdividing the same into segments and 80 said separated segments having walls of different radius for guiding the centrifuged liquids into different outlets.
6. A centrifugal machine as claimed in 85 claim 1, wherein the cell drum forms a grid with separate cells lying next to one another and over one another.
7. A centrifugal machine as claimed in 90 claim 1, wherein the cells of the cell drum have the dimensions of the finished product which is to be made.
8. A centrifugal machine as claimed in 95 claim 1, wherein stationary guiding walls are provided for each horizontal row of the articles moulded in the cell drum, for retarding the velocity at which the said moulded articles are thrown out, so as to prevent their being damaged.
9. A centrifugal machine as claimed in 100 claim 1, characterized by the provision of stationary guiding walls for each horizontal row of articles moulded in the cell drum, for 105 retarding the velocity at which the said moulded articles are thrown out, and the guiding walls being inclined with respect to the direction of delivery of the drums.
- In witness whereof I have hereunto signed my name.

VICTOR REDLICH.
